INVENTOR

I. L. ROBBLEE.

BY

Harry A. Styll.

ATTORNEY

UNITED STATES PATENT OFFICE.

IDE L. ROBBLEE, OF SOUTHERBRIDGE, MASSACHUSETTS.

SLED.

Application filed July 9, 1923. Serial No. 650,373.

To all whom it may concern:

Be it known that I, IDE L. ROBBLEE, a citizen of the United States, residing at Southbridge, in the county of Worcester 5 and State of Massachusetts, have invented certain new and useful Improvements in Sleds, of which the following is a specification.

This invention relates to sleds, and has 10 for its leading object the provision of a device which will serve to add to and increase the springiness of a coasting sled, whereby the sled will have considerably more elasticity and spring in its action when taking 15 bumps or bounds than is present in the ordinary type of coasting sled.

A further object of the present invention is the provision of adjusting means whereby the springiness or elastic action of the 20 seating arrangement may be adjusted and regulated within certain limits.

A further object of the invention is the provision of a device of this character in which the parts shall be so related that the 25 elastic or spring action of the sled may be increased or decreased within certain limits and a sport toy provided having characteristics not possessed by prior devices.

Other objects and advantages of the invention should be readily apparent by reference to the following specification taken in connection with the accompanying drawings, and it will be understood that any 30 modifications or departures may be made 35 from the specific features disclosed within the scope of the claim without departing from or exceeding the spirit of the invention, a preferred form only of the device being shown for sake of and by way of illustration.

Figure I is a perspective view of the invention, showing the forward end of the runner flexed or bent up by the weight of the user.

Figure II is a side elevation of the invention showing in dotted lines the spring action of the same.

Figure III is a partial longitudinal cross section on line III—III of Figure I.

Figure IV is a cross section on line IV—IV of Figure II.

Referring to the drawings, 1 is a base or runner board, which is straight, as shown in dotted lines in Figure II, when relieved 55 of the rider's weight, but has an upturned or sprung-up forward portion 2 when in use.

Intermediate the ends of the base or runner board are slide supports 3, in which is held the seat pedestal 4, which is secured in the guides 3 by any suitable arrangement so 60 that the base pedestal 4 may be locked in any position intermediate the ends of the guides 3, as desired, as shown in Figure III. The pedestal 4 is secured to the top or seat board by the bolts 7, but the pedestal 4 is 65 not locked to the base or runner board 1 but is free to slide in the guides 3 both longitudinally and up and down, the guides 3 being of a height sufficient to prevent the pedestal 4 from jumping out from between 70 the guides 3 when the sled is being used with someone on the seat. The pedestal 4 is held by the guides 3 from sidewise motion. A straight top or seat board 5 is secured to the runner board 1 at the front end by the bolts 75 6, and to the pedestal support 4 by the bolts 7. Additional bolt holes 8 are provided in the seat board 5, as shown in Figures I and III so that the position of the pedestal 4 80 may be changed from its intermediate position either in a forward or backward direction, as desired. A seat 9 is also secured to the seat board 5. A foot rest 10 is secured to the seat board 5 by the bolts 11 and additional bolt holes 12 are provided in the seat 85 board 5 so that the foot rest may be shifted from its intermediate position 11 either forwards or backwards as desired in a manner similar to the way the pedestal 4 is shifted.

In Figure IV is shown a cross section 90 through the base board or runner board, which may be grooved at 13 if desired in order to hold the sled true to its course and prevent swerving toward the side.

It will be noted that in action the base 95 board 1 is turned or bent up and an additional spring added thereto by reason of the weight of the rider being placed on the seat 9. This seat being placed to the rear of the pedestal 4, has a fulcruming or lever action 100 tending to draw up the front end of the base board and increase the springiness of the sled as a whole. This lever action may be increased or decreased by shifting the pedestal out from its central position either forwards or backwards to the position 8. The pedestal 4 is free to move up and down in the guides 3, also to slide back and forth longitudinally therein when the pedestal is shifted from position 7 to position 8, and 105 also has an oscillatory movement in the guides about the bottom end as a fulcrum 110

when the top piece changes its angle with respect to the runner through its spring action under the application of weight and encountering varying surface conditions.

5 The runner board being placed under tension by the weight of the rider, the whole structure is very elastic, so that when the sled goes over an unevenness in the ground, such as a bump, the sled will have a tendency to bound upward and is very springy in its action, increasing the effect of the bumps and unevennesses that are gone over.

10 The sled may be made with one runner, as shown, or it can be provided with two or 15 more runners or base boards separated one from the other, as desired.

15 It will, of course, be understood that the base runner is made from a thin elastic wood or material that may be tensed, as has been 20 described hereinabove.

From the foregoing description it will be seen that I have provided a simple and effi-

cient means for constructing a sled very springy and elastic in its action and very simple and cheap in its construction and 25 maintenance.

I claim:

In a sled, an unbent flexible runner, an unbent top piece having a seat portion joined at the forward end of the runner and 30 forming an angle therewith, an inflexible pedestal piece between the top piece and the runner intermediate the ends of the runner and top piece, rigidly secured to the top piece to prevent lateral movement of the 35 pedestal, but free and unsecured as respects the runner and so positioned with respect to the seat portion that the weight of the operator on the seat portion will bend up the front end of the runner to form the usual 40 upturned runner portion, and at the same time provide a resilient seat for the operator.

IDE L. ROBBLEE.
